CLAIM

The ornamental design for a balloon distress signal kit, as shown and described.

DESCRIPTION

FIG. 1 is a perspective view of a balloon distress signal kit showing my new design;

FIG. 2 is a front elevational view thereof, with the rear being a mirror image, with the omission of the balloon; FIG. 3 is a side elevational view thereof, with the opposite side being a mirror image;

FIG. 4 is a top plan view thereof; and,

FIG. 5 is a bottom plan view thereof.

FIG. 3.

FIG. 2.

FIG. 5.

FIG. 4.
